UNITED STATES PATENT OFFICE.

JAMES F. LOCKWOOD, OF PHILADELPHIA, PENNSYLVANIA.

DESIGN FOR A TOILET-CASE.

SPECIFICATION forming part of Design No. 18,676, dated October 9, 1888.

Application filed August 3, 1888. Serial No. 281,887. Term of patent 3½ years.

To all whom it may concern:

Be it known that I, JAMES F. LOCKWOOD, a citizen of the United States, and a resident of Philadelphia, Pennsylvania, have invented a 5 new and original Design for a Toilet-Case, of which the following is a specification.

My design is fully shown in the accompanying drawing, which represents a perspective view of the toilet-case.

10 The leading features of the design are the back A, with central rectangular panel, B, and tapering receptacles D D on opposite sides of the same, and the projecting tray F at the base, minor features of the ornamentation being the 15 perforated front and ends G G' of said tray, the roughened bottom of the same, the rope-

like bead a around the upper portion of the tray, the rope-like bead b near each edge of the back, and the projecting ornaments d and central fan-like ornaments, f, at the top of said back. 20

I claim—

The design for a toilet case, substantially as described and shown.

In testimony whereof I have signed my name 25 to this specification in the presence of two subscribing witnesses.

JAMES F. LOCKWOOD.
